UNITED STATES PATENT OFFICE.

WILLIAM MONROE WHITE, OF MILWAUKEE, WISCONSIN.

GOVERNOR.

1,355,294.

Specification of Letters Patent. Patented Oct. 12, 1920.

Application filed September 15, 1917, Serial No. 191,890. Renewed March 8, 1920. Serial No. 364,311.

To all whom it may concern:

Be it known that I, WILLIAM MONROE WHITE, a citizen of the United States, residing at Milwaukee, in the county of Milwaukee and State of Wisconsin, have invented a certain new and useful Improvement 5 in Governors, of which the following is a specification.

This invention relates to improvements 10 in speed governors for energy-translating machines.

An object of the invention is to provide a speed governor which is simple in construction and efficient in operation.

15 One of the more specific objects of the invention is to provide a governor which is exceedingly sensitive to variations in speed and which is more reliable in operation than the governors of the prior art. It has been 20 customary in most governors of the prior art to utilize a great many bearing surfaces, the overheating of any one of which necessitated shutting down the machine controlled by the governor. In the device of 25 the present invention frictional engagement between relatively moving parts, is reduced to a minimum and means are provided whereby the governor may be quickly disconnected and the prime mover controlled 30 manually in case of excessive overheating of the governor bearing surfaces.

Another specific object is to provide simple and efficient means for transmitting motion from the weights or fly balls of a centrifugal 35 governor to the mechanism controlled thereby.

A further specific object is to provide a speed governor especially adapted for direct connection to the main shaft of an energy-translating device. While the governor of the present invention is directly applicable to either horizontally or vertically disposed shafts, its application to the vertical main shafts of direct connected vertical 45 hydro-electric energy-translating machines is especially desirable since such application permits reduction to a minimum of the overall height of the powerhouse. It is customary in the construction of vertical 50 hydro-electric units to mount the generators directly upon the main shafts above the turbines. Traveling cranes located above the generators serve to handle heavy machine parts during installation and in case

removal of such parts is necessary. The 55 location of these cranes depends upon the length of shafting between the turbines and the generators, and the height of the building is determined by the location of the crane. It is therefore desirable to make the 60 distance between the generators and the turbines as short as possible, in order to reduce to a minimum the overall height and hence the cost of construction of the building. In existing designs of hydro-electric units, 65 the governors are ordinarily driven by means of horizontal jack shafts which are driven by bevel gearing associated directly with the main shafts of the units. In order to permit inspection of this gearing and 70 to eliminate danger of injury by contact with the revolving jack shafts, it is necessary to allow a considerable space above the floor of the turbine pit and below the horizontal jack shafts. The allowance of 75 this space necessitates lengthening the main shafts and also in most cases necessitates making the supports for the generators considerably larger and heavier than would otherwise be necessary. By utilizing the 80 present invention, the horizontal jack shafts and connecting gearing are eliminated, the governors being mounted directly upon the main shafts, thereby permitting utilization of relatively short main shafts, eliminating 85 danger of injury during inspection, and reducing to a minimum the overall height of the units and of the power house.

Still another object of the invention is to provide a governor which may be directly connected to horizontal or vertical shafts which during normal operation reciprocate or "float" a slight amount. The invention contemplates the provision of means whereby the motion of the governor weights is 90 alone transmitted to the device controlled by the governor, regardless of longitudinal movement of the main shaft. In some turbines there is a longitudinal reciprocating movement of the main shaft due to unbalanced forces acting upon the runner. In utilizing the direct connected governor, if no provision is made for compensating for such movement of the main shaft, this movement will be transmitted to the device 95 controlled by the governor. The present invention therefore contemplates the provision of means whereby only the motion of 100

105

the governor collar relative to the main shaft, is transmitted to the mechanism controlled by the governor.

A clear conception of several embodiments of the invention may be had by referring to the drawings accompanying and forming a part of this specification, in which like reference characters designate the same or similar parts in the various views.

Figure 1 is a diagrammatic part sectional view of a hydro-electric installation having a governor mounted directly upon the main shaft thereof between the turbine and generator.

Fig. 2 is an enlarged part sectional front elevation of a governor mounted directly upon the main vertical shaft of an energy translating device.

Fig. 3 is an enlarged part sectional side elevation of the governor disclosed in Fig. 2, the section being taken along the line III—III of Fig. 2 looking in the direction of the arrows.

Fig. 4 is an enlarged front elevation of a governor mounted directly upon a longitudinally reciprocable horizontal shaft.

Fig. 5 is an enlarged side elevation of the governor disclosed in Fig. 4.

Fig. 6 is an enlarged end elevation of the governor disclosed in Figs. 4 and 5.

Fig. 7 is an enlarged front elevation of another form of governor mounted directly upon a longitudinally reciprocable horizontal shaft.

Fig. 8 is a fragmentary diagrammatic part sectional view of a hydro-electric installation showing a modified form of governor motion-transmitting mechanism.

The hydro-electric installation to which the governor is disclosed as applied in Fig. 1, comprises an energy-translating device or Francis turbine 5 direct connected to the lower extremity of a vertical main shaft 1, the upper extremity of which has directly connected thereto the rotor of an energy-absorbing device or electric generator 4. The Francis turbine 5 is operated in the usual manner by means of water under pressure admitted from the penstock through the spiral casing 11 past the circular series of adjustable guide vanes 10. The discharge of the turbine 5 communicates with the usual tailrace through a draft tube 12. The guide vanes 10 are adjustable by means of a servo-motor 9 controlled by mechanism 7 which controls the flow of actuating fluid through pipes 8 to the servo-motor 9. The mechanism 7 as disclosed in Figs. 1, 2 and 3 is controlled by means of the speed governor through a bifurcated bell crank 17 pivotally mounted upon a stationary casing 19, and a motion-transmitting connection 6 housed within a protecting casing or tube 18.

The speed governor, see Figs. 2 and 3,

comprises a movable element or collar 3 surrounding but spaced slightly from the main shaft 1, and a pair of diametrically opposite weights 2 pivotally suspended from a collar fixed to the main shaft 1. Each of the weights 2 has an integral projection 19 extending inwardly from the upper end thereof and pivotally connected to the supporting ring on the main shaft 1. The weights 2 are connected with the movable element or collar 3 by means of links 14, which links together with the weight projections 19 constitute diametrically opposite toggle connections between the shaft 1 and the collar 3. The collar 3 is also connected to the main shaft 1 by means of diametrically opposite toggles consisting of upper links 15 pivoted directly to the collar 3 and lower links 16 pivoted to the fixed shaft collar and pivotally connected to the links 15. The links 14, 15, 16 and the weights 2 are of considerable width measured transversely of the shaft 1, thus positively constraining the toggles to motion in planes perpendicular to their connecting pivots.

The floating collar 3 is provided with an annular recess 22 within which bearing shoes 20 carried by extremities of the bifurcations of the bell crank 17, are slidable. The recess 22 may be provided with suitable lubricant and the shoes 20 may be provided with antifriction bearing means, in order to reduce the friction to a minimum. The weights 2 are connected to each other by springs 13 located one on each side of the shaft 1, and are prevented from moving inwardly and outwardly beyond predetermined limiting positions, by means of stops 21 which engage abutment surfaces formed on the weights. Excessive outward distortion of the springs 13, due to the action of centrifugal force thereon, is prevented by means of stops 23.

In the form of governor disclosed in Figs. 4, 5 and 6, the general construction of the weights 2, toggles 14, 15, 16 and collar 3 is the same as that disclosed in Figs. 2 and 3. In this embodiment the main shaft 25 is arranged horizontally instead of vertically and is presumed to have a longitudinal reciprocating or floating movement which it is not desired to have transmitted to the devices controlled by the governor. The bifurcated lever 27 comprises two arms extending to points on opposite sides of the shaft 25 and carrying shoes 20 which engage the collar 3. The arms of the lever 27 are rigidly joined by means of a pin 29 which is pivotally supported in a bearing at the mid-portion of one arm of a bifurcated bell-crank 28. One arm of the lever 27 is provided with an integral projection extending longitudinally of the main shaft 25, the extreme end of which projection is connected with one end of a lever 31, by means of a

connection 30. The lever 31 has its mid-portion pivotally connected to the end of another arm of the bell-crank 28, by means of a pivot 32. The opposite end of the lever 31 is connected with the controlling mechanism 7, by means of a connection 34. The bifurcated bell-crank 28 is pivotally mounted upon a stationary support 33 and has its bifurcations connected with a collar 26 secured to the shaft 25, by means of pivots 35 engaging slightly elongated openings in the bell-crank 28, these openings compensating for angular displacement of the bell-crank 28 relatively to the shaft 25 about the pivot support 33.

In the form of governor disclosed in Fig. 7, the general construction of the weights 2, toggles 14, 15, 16 and collar 3 is again the same as that disclosed in Figs. 2 and 3. The main shaft 25 is horizontally disposed and has a reciprocating motion, as in Figs. 4, 5 and 6. The bifurcated lever 37 comprises two arms extending to points on opposite sides of the shaft 25 and carrying shoes 20 which engage the collar 3. The arms of the lever 37 are rigidly joined by means of a pin 39 which is pivotally supported in a bearing at the mid-portion of a bifurcated lever 38. One arm of the lever 37 is provided with a projection the end of which is connected with the controlling mechanism 7, by means of a connection 44. The bifurcated lever 38 is pivotally mounted upon a stationary support 43, and has its bifurcations connected with a collar 26 secured to the shaft 25, by means of pivots 45 engaging slightly elongated openings in the lever 38, these openings compensating for angular displacement of the lever 38 relatively to the shaft 25 about the pivot support 43.

The means for transmitting the governor motion from the bell-crank 17 to the controlling mechanism 7, disclosed in Fig. 8, provides for greater overhead clearance in the turbine pit, than is provided in the arrangement shown in Fig. 1, and by the devices of the prior art. The motion transmitting mechanism of Fig. 8 comprises a pair of connections 60, 61 and an idler bell-crank 62 pivotally mounted upon a bracket secured to the frame of the generator 4. With this arrangement of connections and levers, maximum headroom is provided above the inspection walk of the turbine pit.

During normal operation of the device disclosed in Figs. 1, 2 and 3, the main shaft 1 is rotated by the turbine 5, and the weights 2 of the governor are moved outwardly by centrifugal force, against the tension of the helical springs 13. This outward movement of the weights 2 causes the pivotal connections between the projections 19 of the weights 2 and the links 14 to move upwardly, thereby causing the links 14 to move longitudinally of the shaft 1, and to raise

the floating collar 3. During this movement of the weights 2, links 14 and collar 3, the toggles formed by the links 15, 16 are straightened and prevent movement of the collar 3 transversely of the shaft 1. As the speed of the shaft 1 varies, the weights 2 move toward and away from the shaft 1 causing the collar 3 to assume various positions along the shaft. The motion of the collar 3 is transmitted through the shoes 20, 75 bifurcated bell-crank 17 and connection 6 to the servo-motor controlling mechanism 7, thereby causing variations in the position of the servo-motor and of the guide vanes 10, and regulating the speed of the turbine 5. 80

With the device disclosed in Figs. 4, 5 and 6, if the shaft 25 is not moving longitudinally, motion of the collar 3 is transmitted to the bifurcated bell-crank 27, causing this bell-crank to swing about the axis of the pin 85 29. This swinging motion of the crank 27 is transmitted through the connection 30 to the lever 31 which is simultaneously swung about the pivot 32 causing the connection 34 to move and to actuate the controlling mechanism 7. If the shaft 25 moves longitudinally, such motion is transmitted to the bifurcated bell-crank 28 through the collar 26 and pins 35, causing the bell-crank 28 to swing about the stationary pivot support 33. 90 As the bell-crank 28 swings about the support 33, the pivots 29, 32 are moved distances proportional to the respective distances between the axes of these pivots and the axis of the pivot on the support 33. The motion 100 of the shaft 25 which moves the bell-crank 28, is also transmitted through the governor to the bell-crank 27, connection 30 and lever 31, but due to the construction and mounting of these elements, the motion of the 105 shaft 25 is entirely compensated for and does not affect the connection 34.

In the embodiment disclosed in Fig. 7, if the shaft 25 is not moving longitudinally, motion of the collar 3 is transmitted through 110 the bifurcated lever 37 directly to the connection 44. If the shaft 25 moves longitudinally, such motion is transmitted to the lever 38 through the collar 26 and pins 45, causing the lever 38 to swing about the stationary pivot support 43. As the lever 38 swings about the support 43, the pivot 39 is moved a distance proportional to the distance from its axis to the axis of swing of the lever 38. The motion of the shaft 25 115 which moves the lever 38, is also transmitted through the governor to the lever 37, but due to the movement of the pivot pin 39 simultaneously with the movement of the ends of the lever 37 adjacent the shaft 25, and 120 the location of the opposite end of the lever 37 directly over the pivot support 43, the shaft motion is compensated for and does not affect the connection 44.

It will be noted that the toggles consisting 130

of the links 15, 16 are movable in a plane at right angles to the plane of movement of the toggles consisting of the links 14 and weight projections 19. The planes of movement of these two sets of toggles intersect at a straight line which substantially coincides with or is parallel to the axis of the shaft 1, thereby always insuring that the collar 3 will remain out of engagement with the shaft 1 and thereby eliminating friction losses. The toggle links 14, 15, 16 constitute the sole means for supporting and guiding the collar 3, thereby reducing the friction to a minimum and producing a governor of maximum sensitiveness. The toggles, so far as their effect is concerned, may be regarded either as the links 14 constrained at one end by any structure such as the weight projections 19, to move the collar 3 longitudinally of the shaft 1, or they may be considered as comprising the weight projections 19 coacting in any manner with the collar 3 to move the same along the shaft 1. In the construction disclosed, the effects of the two links constituting each toggle, are added. In any case, the toggles whether they be of the single or of the double link type, should constitute the sole means for supporting and guiding the collar 3 in order to reduce to a minimum the friction. While the toggles are disclosed as arranged in diametrically opposite pairs, this arrangement being preferred for the purpose of balancing the elements, it will be apparent that only two toggles movable in different planes are essential in order to produce the desired rectilinear motion.

By mounting the governor directly upon the main turbine shaft, the use of a special governor supporting shaft is avoided and the speed changes are transmitted directly from the main shaft to the governor fly-balls, thereby reducing friction losses to a minimum. The devices disclosed in Figs. 4, 5, 6 and 7 provide simple and efficient means for compensating for longitudinal motion of the main shaft. By arranging the governor vertically as disclosed in Figs. 1, 2, 3 and 8, the elements may be readily balanced, thereby also enhancing the sensitiveness of the device. The elimination of rotating motion transmitting mechanism eliminates danger of injury to operators and permits substantial reduction in power house height.

If for any reason it is desired to disconnect the governor and to control the servo-motor 9 manually, this may be done by swinging the bell-crank 17 away from the floating collar 3, thereby breaking the connection between the governor and the motion-transmitting mechanism. The guide vanes 10 may then be regulated manually in the usual manner by means of controlling

valves such as ordinarily provided for manual control of the servo-motor 9.

It should be understood that it is not desired to limit the invention to the exact details of construction herein shown and described, for obvious modifications within the scope of the appended claims may occur to a person skilled in the art.

It is claimed and desired to secure by Letters Patent:

1. In a governor, a support rotatable about an axis, an element spaced from said support and movable longitudinally of said axis, a plurality of toggles connecting said support and said element, and means for actuating at least one of said toggles, said toggles constituting the sole means for guiding said element.

2. In a governor, a support rotatable about an axis, an element movable longitudinally of said axis, a plurality of toggles connecting said support and said element, and means for actuating at least one of said toggles, said toggles constituting the sole means for supporting said element.

3. In a governor, a support rotatable about an axis, an element movable longitudinally of said axis, a plurality of toggles connecting said support and said element, one of said toggles being movable in a plane intersecting the plane of movement of another and said toggles constituting the sole means of support for said element, and a weight movable by centrifugal force to actuate at least one of said toggles.

4. In a governor, a support rotatable about an axis, an element spaced from said support and movable longitudinally of said axis, a plurality of toggles connecting said support and said element, one of said toggles being movable in a plane intersecting the plane of movement of another and said toggles constituting the sole means for guiding said element, and a weight for actuating at least one of said toggles.

5. In a governor, a shaft rotatable about an axis, a collar spaced from and surrounding said shaft, a plurality of toggles connecting said shaft and said collar, and a weight for actuating at least one of said toggles whereby said collar is moved longitudinally of said axis.

6. In a governor, a shaft rotatable about an axis, a collar surrounding said shaft and movable longitudinally of said axis, a plurality of toggles connecting said shaft and said collar, and a weight for actuating at least one of said toggles, said toggles constituting the sole means for guiding and supporting said collar.

7. In a governor, a shaft rotatable about an axis, a collar spaced from said shaft and movable longitudinally of said axis, a pair of toggles connecting said shaft and said

5 collar, each of said toggles being movable only in a plane intersecting the plane of movement of the other and said axis coinciding with the line of intersection of said 10 planes, and a weight for actuating at least one of said toggles.

10 8. In a governor, a shaft rotatable about an axis, a collar spaced from said shaft and movable longitudinally of said axis, a plurality of diametrically opposite pairs of toggles connecting said shaft and said collar, each pair of said toggles being constructed to permit motion only in a plane intersecting the plane of movement of the other and 15 said axis coinciding with the line of intersection of said planes, and weights for actuating at least one pair of said toggles.

15 9. In a governor, a shaft rotatable about an axis, a collar spaced from said shaft and movable longitudinally of said axis, two diametrically opposite pairs of toggles connecting said shaft and said collar, one pair of said toggles being movable in a plane at right angles to the plane of movement of the 20 other and said axis coinciding with the line of intersection of said planes, and a pair of diametrically opposite weights for actuating one pair of said toggles.

20 10. In a governor, a shaft, a collar surrounding said shaft, and a plurality of toggles for moving said collar longitudinally of said shaft, said toggles constituting the sole means for supporting and moving said collar.

25 11. In a governor, a shaft rotatable about an axis, a weight, a collar movable longitudinally of said axis, a connection between said weight and said shaft, a link connecting said weight and said collar, and links connecting said shaft and said collar, said links constituting the sole means of support for 30 said collar.

30 12. In a governor, a shaft rotatable about an axis, a weight, a collar surrounding and spaced from said shaft, said collar being movable longitudinally of said axis, a connection between said weight and said shaft, a link pivotally connected with said weight and said collar, and a pair of pivotally connected links connecting said shaft and said 35 collar.

35 13. In a governor for an energy-translating device, the combination with the main shaft of said device, of a collar surrounding and spaced from said shaft, a weight supported from said shaft, and means for communicating motion from said weight to said collar.

40 14. In a governor for an energy-translating device, the combination with the main shaft of said device, of a collar surrounding and spaced from said shaft, a weight supported from said shaft, means connecting said weight and said collar, and 45 means connecting said shaft and said collar,

said connecting means constituting the sole means for guiding and supporting said collar.

15. In a governor for an energy-translating device having a vertical main shaft, the 70 combination of a collar spaced from and surrounding said shaft, a weight pivotally supported from said shaft, a link connecting said weight and said collar, and a pair of pivoted links connecting said shaft and 75 said collar, said links constituting the sole means of guiding and supporting said collar.

16. In a governor, a shaft rotatable about an axis, a weight, a collar movable longitudinally of said axis, a connection between said weight and said shaft, a link connecting said weight and said collar, and links connecting said shaft and said collar, said links having a pair of bearing points spaced 80 apart to permit motion of said links in only one plane.

17. In a governor, a shaft movable longitudinally of its axis, a governing device supported directly by said shaft, means for 90 transmitting motion from said governor, and means for preventing longitudinal movement of said shaft from affecting the governor motion.

18. In combination, an energy-translating 95 device, a speed governor mounted upon the main shaft of said device, means for controlling the speed of said device, means for transmitting motion from said governor to said controlling means, and means for compensating for axial movement of the main 100 shaft of said device whereby such axial movement will not affect said controlling means.

19. In combination, a shaft having axial 105 play, a centrifugal governor mounted upon said shaft, said governor comprising a collar surrounding and having motion axially of said shaft, means controlling the energy delivered to said shaft, and means for transmitting to said controlling means only the relative axial motion of said collar and said shaft.

20. In combination, an axially reciprocable shaft, a collar surrounding said shaft 110 and movable longitudinally thereof, and means for transmitting from said collar only relative axial motion of said collar and said shaft.

21. In a governor, a rotary shaft, a collar 115 movable longitudinally of said shaft, a plurality of toggles each comprising a pair of connected members connecting said collar and said shaft, and a plurality of bearings between each two of said connected parts, 120 namely, said shaft, said collar and said toggle members.

22. In a governor, a rotary shaft, a collar 125 movable longitudinally of said shaft, a plurality of toggles each comprising a pair of 130

connected links connecting said collar and said shaft, and a plurality of spaced coaxial bearings between each two of said connected parts, namely, said shaft, said collar and said toggle links.

23. In a governor, a shaft rotatable about an axis, a collar movable longitudinally of said shaft, a plurality of toggles connecting said shaft and said collar, each toggle com-

prising two directly pivotally connected links movable only in planes parallel to or coincident with said axis, and the planes of movement of at least one toggle intersecting planes of movement of another, and weights for moving said toggles.

In testimony whereof the signature of the inventor is affixed hereto.

WILLIAM MONROE WHITE.
